Goro Nishikata, Kawasaki, Japan, assignor to Kabushiki
Kaisha Mitutoyo Seisakusho, Tokyo, Japan

Filed Aug. 29, 1974, Ser. No. 502,041

Claims priority, application Japan Mar. 8, 1974

Term of patent 14 years

Int. Cl. D22—05

U.S. Cl. D22—5

FIG. 1

FIG. 2

FIG. 3

FIG. 4

FIG. 7

FIG. 5

FIG. 6

FIG. 1 is a front elevational view showing my design for a sight for an archery bow;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of the bow when in actual use.

I claim:

The ornamental design for a sight for an archery bow, as shown and described.
